UNITED STATES PATENT OFFICE.

JAMES D. ADAMS AND AUGUST G. JOHNSON, OF MONESSEN, PENNSYLVANIA,
ASSIGNORS TO PITTSBURGH STEEL CO., A CORPORATION OF PENNSYLVANIA.

REEL.

1,098,655.

Specification of Letters Patent. Patented June 2, 1914.

Application filed November 6, 1912. Serial No. 729,845.

To all whom it may concern:

Be it known that we, JAMES D. ADAMS and AUGUST G. JOHNSON, citizens of the United States, and residents of Monessen, 5 in the county of Westmoreland and State of Pennsylvania, have invented a new and useful Improvement in Reels; and we do hereby declare the following to be a full, clear, and exact description thereof.

10 Our invention relates to reels for holding barb wire, plain wire, or like material.

The object of our invention is to provide a strong and rigid reel formed of wire which will support the wire when wound thereon 15 and will stand the rough usage to which such reels are subjected in handling and shipping.

A further object of our invention is to provide a reel of this character which is 20 collapsible, the parts being capable of separation so that when the reel has been emptied it may be taken apart and shipped back to the mill to be used again.

To these ends our invention comprises the 25 novel features hereinafter set forth and claimed.

In the accompanying drawing Figure 1 is a perspective view of our improved reel; Fig. 2 is a plan view of the spacing members 30 with a portion of the end-members shown in section; Fig. 3 is a view of one of the arms of the end-member showing the spacing member in section engaging therewith; and Fig. 4 shows a modified form of 35 our invention.

In the drawing the numeral 2 designates the end-members of our improved reel which are substantially star-shaped and are formed of wire of proper gage to give the 40 required strength and rigidity as well as the necessary resiliency. These end members are preferably formed of one piece of metal and the free ends are welded together by electricity or any other suitable method.

45 The end-members have the radiating arms 3 which are preferably slightly tapering and said arms are bent to form the depressions 4. The tie-rods 5 are likewise formed of wire of suitable thickness and the ends 50 of said tie-rods are bent to form the loops 6 at each end thereof. These loops are adapted to engage the arms 3 of the end members at the depressions 4 and in assembling the members of the reel the loops 6 of the tie-

rods are slipped over the ends of the arms 55 of the end members and sufficient pressure applied to overcome the resistance due to the increasing width of the arms from their outer to their inner ends, and the resiliency of the metal will permit said arms to yield 60 sufficiently to allow the loops to be forced down over said arms until the depressions 4 are reached, whereupon the loops will seat themselves in said depressions and the arms which have been contracted by the loops in 65 moving over them will expand and so act to lock the tie-rods securely in position against further inward as well as outward movement. In this manner the reel is built up of the end-members with the tie-rods 70 connecting the same and spacing the end-members at proper distances and the parts when united in this manner form a rigid, strong structure which can bear the weight 75 of the wire wound thereon without liability of collapsing, either during the winding of the wire thereon or during shipment. By the use of rods with loops at the end thereof, the loop surrounds the arm and a very secure interlocking of the tie-rod with the 80 arm is obtained. Furthermore, when the reel is empty it may be taken apart by forcing the loops of the tie-rods out over the arms of the end-members and the parts can then be shipped back in convenient bundles 85 to the factory to be used again.

In Fig. 4 we have illustrated a slightly modified form of our invention in which the shoulder 8 is formed on the arm of the end-member and the loop 9 of the tie-member 90 engages this shoulder, the resiliency of the metal of the arm acting to prevent the outward movement of the tie-member.

What we claim is:

1. A reel comprising end members each 95 of which consists of a single piece of wire bent to form without intersecting three or more radiating arms, and tie-rods having loops at the ends thereof engaging the inner ends of said arms.

2. A reel comprising end members each of which consists of a single piece of wire bent to form without intersecting three or more radiating arms, said arms having seats bent therein, and tie-rods having loops at the 100 ends thereof engaging said arms at said seats.

3. A reel comprising end members each

of which consists of a single piece of wire
bent to form without intersecting three or
more radiating arms, said arms having de-
pressions bent therein, and tie-rods having
loops at the ends thereof engaging the de-
pressions in said arms.

In testimony whereof, we the said JAMES

D. ADAMS and AUGUST G. JOHNSON have
hereunto set our hands.

JAMES D. ADAMS.
AUGUST G. JOHNSON.
